DESIGN FOR A DISPENSING FAUCET

Frederick C. Picut, Westfield, N. J.

Application August 28, 1944, Serial No. 115,065

Term of patent 14 years

(Cl. D91—3)

To all whom it may concern:

Be it known that I, Frederick C. Picut, a citizen of the United States, residing at Westfield, county of Union and State of New Jersey, have invented a new, original, and ornamental Design for Dispensing Faucets, of which the following is a specification, reference being had to the accompanying drawing, forming a part thereof.

Figure 1 is a top plan view of the dispensing faucet showing my new design.

Figure 2 is a side elevation of the dispensing faucet.

Figure 3 is a front elevation of the dispensing faucet.

Figure 4 is a bottom plan view of the dispensing faucet.

I claim:

The ornamental design for a dispensing faucet, as shown.

FREDERICK C. PICUT.
